MUSICAL RHYTHM-PRODUCING TOY

Aaron I. Brown, Mount Vernon, N. Y.

Application September 15, 1950, Serial No. 185,132

2 Claims. (Cl. 46—191)

1

This invention relates to musical toys, and more particularly to a sounding device of the clapper type.

A main object of the invention is to provide a novel and improved musical toy which is very simple in construction, which is easy to use, and which may be operated to give rhythmic sounds similar to drum beats or the sounds produced in tap dancing.

A further object of the invention is to provide an improved clapper toy which is very inexpensive to manufacture, which is sturdy in construction, which is very easy to use, and which provides a substantial degree of entertainment.

Further objects and advantages of the invention will become apparent from the following description and claims, and from the accompanying drawings, wherein:

Figure 1 is a top plan view of one form of musical toy constructed in accordance with the present invention;

Figure 2 is a side elevational view of the musical toy of Figure 1;

Figure 3 is an enlarged, cross-sectional, detail view taken on line 3—3 of Figure 1;

Figure 4 is a fragmentary elevational view of the connected end portions of the sounding elements of the toy in a modified form of the invention;

Figure 5 is a top plan view of the structure shown in Figure 4;

Figure 6 is an enlarged, cross-sectional view taken on line 6—6 of Figure 5.

Referring to the drawings, and more particularly to Figures 1, 2 and 3, the sounding device is designated generally at 11 and may comprise a pair of identical spoons 12, 12 arranged with their bowl portions 13 positioned back to back, as shown. Designated at 14 is a U-shaped leaf spring whose ends are fastened by rivets 15 to the ends of the respective spoons 12. Alternatively, the ends of the leaf spring may be soldered, welded, or rigidly secured to the ends of the spoons in any other suitable manner. As a further alternative, the spring may be made integral with the spoons. With the ends of the spoons 12, 12 thus connected, the spring 14 maintains said spoons in the plane of the spring, but allows the spoons to oscillate in said plane relative to each other. In using the toy, the device is held in one hand and one of the spoons is separated from the other and allowed to spring back, whereby the bowl portion of one spoon strikes the bowl portion of the other spoon, producing a loud sound. The operator of the device

2

rhythmically separates the spoons and allows them to spring back, thereby producing the rhythmic sounds simulating the sounds of a tap dancer or the sounds produced by a drum. Another method of use is to hold the spoons loosely in one hand and, by striking the lower spoon against one thigh (the user being seated), or by striking the thighs alternately with the spoons, one spoon is made to click against the other spoon by the yieldability of the spring and the inertia of the spoons. Repeated periodic beats may be thus produced, following the rhythm of music and simulating the sound of tap dancing or drum beats.

15 Instead of employing spoons, any suitable pair of identical members having concavely bowed portions may be employed in the device, such as a pair of knives or a pair of forks, and the members may be made of any suitable material, such as metal, wood, plastic, or the like.

Referring now to Figures 4, 5 and 6, the spoons or other similar sounding elements are designated at 12', 12', and the U-shaped spring member is designated at 14'. Designated at 15', 15' are 25 sleeve members of elastic material, such as rubber or the like, which are secured to the respective ends of the leaf spring 14' and tightly receive the ends of the sounding members 12', 12', as shown. The sleeve members 15', 15' provide secure connections of the ends of the sounding members 12', 12' to the ends of the leaf spring 14', whereby the sounding members will be resiliently connected together in substantially the same manner as in the embodiment of the invention shown in Figures 1, 2 and 3.

35 The leaf spring 14 or 14' may have any suitable configuration, and may be formed with multiple bowed portions, or may be otherwise suitably formed, if so desired.

40 While certain specific embodiments of an improved sounding toy or clapper have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A clapper of the character described comprising a pair of spoons arranged back-to-back, each spoon having a bowl portion, the respective bowl portions of the spoons being disposed adjacent each other, and a U-shaped leaf spring secured to and connecting the ends of the spoons, whereby the bowl portion of one spoon will strike

the bowl portion of the other spoon when the spoons are separated and then released.

2. A clapper of the character described comprising a pair of spoons arranged back-to-back, each spoon having a bowl portion, the respective bowl portions of the spoons being disposed adjacent to each other, a U-shaped leaf spring, and respective sleeves of elastic material on the ends of the leaf spring and tightly receiving the ends of the spoons, connecting the ends of the spoons to the leaf spring, whereby the bowl portion of one spoon will strike the bowl portion of the other spoon when the spoons are separated and then released.
